UNITED STATES PATENT OFFICE.

CONRAD H. ZIEG, OF YORK, NEBRASKA.

FURNACE.

Application filed April 6, 1922. Serial No. 550,064.

To all whom it may concern:

Be it known that I, CONRAD H. ZIEG, a citizen of the United States, residing at York, in the county of York and State of Nebraska, have invented a new and useful Furnace, of which the following is a specification.

This invention relates to furnaces and more particularly to furnaces of the hot-air type, the primary object of the invention being to provide a furnace wherein the maximum amount of heat will be generated from the minimum amount of fuel.

Another object of the invention is to provide a furnace wherein the smoke and gases which ordinarily pass upwardly through the chimney will be directed through the body of the furnace to further heat the furnace.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a furnace constructed in accordance with the present invention.

Figure 2 is a sectional view taken on line 2—2 of Figure 1.

Figure 3 is a sectional view taken on line 3—3 of Figure 4.

Figure 4 is a sectional view taken on line 4—4 of Figure 1.

Figure 5 is a sectional view taken on line 5—5 of Figure 2.

Figure 6 is a sectional view taken on line 6—6 of Figure 2.

Figure 7 is a sectional view taken on line 7—7 of Figure 4.

Referring to the drawings in detail, the furnace is indicated generally by the reference character 5 and is constructed of bricks or other well known material employed in furnace construction. The furnace is formed with a firebox indicated at 6, which extends from the front of the furnace, terminating at a point at the rear thereof. The firebox 6 is also formed with side walls 7, which are disposed in spaced relation with the side

walls of the furnace to provide passageways 8, the passageways being in communication with the firebox, as through the chamber 9, disposed at the rear thereof.

As shown, the side walls 7 of the firebox continue to the upper portion or top of the stove indicated at 10, providing lateral passageways, which passageways are divided by the partitioning walls 11, which have their lower ends disposed in spaced relation with the firebox top 12 to insure the heat and products of combustion circulating through the upper portion of the furnace, and at the same time restricting the passage of heat to increase the suction or draft through the passageways.

The central portion of the furnace is divided by a wall 13, which extends to a point in spaced relation with the top 10 of the furnace to provide a passageway 14 which is in communication with the central passageway as through the opening 13'. At the forward portion of the furnace is a wall 15 which forms a part of the chimney 16, the lower end of the wall 15 terminating in spaced relation with the upper wall 12 of the firebox. The furnace is provided with the usual grate indicated at 17 and ash-pit 18. From the foregoing it will be seen that the heat and products of combustion are carried twice through the furnace, the heat and products of combustion taking a path through the chamber 9 as indicated by the arrows as shown by Figure 4 of the drawings, from where it passes over and under the partitioning wall 11 and to the central portion of the furnace, through the opening 13', where the same passes upwardly over the wall 13 and to the chimney 16, through the opening at the base of the wall 15 as shown by Figure 2 of the drawings.

Having thus described the invention, what is claimed as new is:—

1. In a furnace construction, a fire-box, said furnace including a central compartment and lateral compartments, said lateral compartments communicating with the fire-box at one end of the fire-box, said lateral compartments communicating with the central compartment at the rear of the furnace, and adjacent to the upper wall of the fire-box, a plurality of vertical walls disposed within the lateral compartments, one of the walls having its lower edge spaced from the upper wall of the fire-box, the opposite walls having their upper ends arranged in spaced

relation with the upper wall of the furnace to provide baffles, and baffles in the central compartment to obstruct passage of products of combustion therethrough.

- 5 2. A furnace construction including a fire-box said furnace including a central passageway and lateral passageways arranged above the fire-box, said lateral passageways being in communication with the fire-box
10 at the rear thereof, means for causing products of combustion passing through the lateral passageways to take an irregular

course therethrough, and baffles in the central passageway causing the products of combustion to take an irregular course 15 through the central passageway.

In testimony that I claim the foregoing as my own, I have hereto affixed my signature in the presence of two witnesses.

CONRAD H. ZIEG.
